CONVERTIBLE TOP FOR A BOAT

John Herman, Chicago, Ill.

Application May 24, 1956, Serial No. 41,640

Term of patent 14 years

(Cl. D71—1)

Fig. 1.

Fig. 2.

Fig. 3.

Fig. 1 is a front perspective view of a convertible top for a boat, showing my new design;

Fig. 2 is a rear perspective view taken from the opposite side of Fig. 1; and

Fig. 3 is a top plan view of the convertible top for a boat.

I claim:

The ornamental design for a convertible top for a boat, substantially as shown.
